(57) **CLAIM**

The ornamental design for an elevator buffer, as shown and described.

DESCRIPTION

FIG. 1 is a perspective view from above and to one side of an elevator buffer.

FIG. 2 is a plan view from above the elevator buffer of FIG. 1. FIG. 3 is a plan view from underneath the elevator buffer of FIG. 1.

FIG. 4 is an elevation view from a first side of the elevator buffer of FIG. 1.

FIG. 5 is an elevation view from a second side the elevator buffer of FIG. 1 orthogonal to the first side.

FIG. 6 is an elevation view from a third side the elevator buffer of FIG. 1 orthogonal to the second side.

FIG. 7 is an elevation view from a fourth side the elevator buffer of FIG. 1 orthogonal to the third side.

FIG. 8 is a perspective view from above and to one side of a second embodiment of an elevator buffer.

FIG. 9 is a plan view from above the elevator buffer of FIG. 8.

FIG. 10 is a plan view from underneath the elevator buffer of FIG. 8.

FIG. 11 is an elevation view from a first side of the elevator buffer of FIG. 8.

FIG. 12 is an elevation view from a second side the elevator buffer of FIG. 8 orthogonal to the first side.

FIG. 13 is an elevation view from a third side the elevator buffer of FIG. 8 orthogonal to the second side; and,

FIG. 14 is an elevation view from a fourth side the elevator buffer of FIG. 8 orthogonal to the third side.
